UNITED STATES PATENT OFFICE.

STEPHEN S. ADAMS, OF ST. LOUIS, MISSOURI.

EMBOSSSED-PLATE-PRINTING MACHINE.

1,175,578.

Specification of Letters Patent. Patented Mar. 14, 1916.

Application filed April 5, 1915. Serial No. 19,170.

To all whom it may concern:

Be it known that I, STEPHEN S. ADAMS, a citizen of the United States, residing at St. Louis, State of Missouri, have invented a certain new and useful Improvement in Embossed-Plate-Printing Machines, of which the following is a full, clear, and exact description, such as will enable others skilled in the art to which it appertains to make and use the same, reference being had to the accompanying drawings, forming part of this specification, in which—

Figure 1 is a side elevational view of a machine of my improved construction, parts thereof being broken away and parts in section in order to more clearly illustrate the construction of the machine. Fig. 2 is an enlarged vertical section taken approximately on the line 2—2 of Fig. 1, and showing a portion of an embossed plate between one of the carrying rollers and one of the inking rollers. Fig. 3 is a vertical section taken lengthwise through the center of the machine and showing the arrangement of the plate carrying rollers, inking rollers, and ink distributing rollers. Fig. 4 is a plan view of the machine. Fig. 5 is an elevational view of a series of sprocket wheels which are carried by the feed rollers and the driving chain thereof. Fig. 6 is an enlarged vertical section taken approximately on the line 6—6 of Fig. 3.

My invention relates generally to printing machinery and more particularly to a machine designed for coloring embossed plates, such as for instance, motor vehicle license plates, embossed advertising plates or any metal or composition plate which is embossed to form raised letters, numbers or characters, and the surfaces of which raised portions are distinctively colored with respect to the back ground or depressed portions.

It will be understood that embossed vehicle license plates and advertising plates are generally coated with a suitable liquid enamel or vitrifiable substance and after the same has been applied it is necessary to "bake" the coated plates in order to cause the enamel or vitrifiable substance to become hardened and set on the plates.

My improved machine is particularly designed for receiving embossed plates after the same have been coated so as to color the back ground and apply to the surfaces

of the raised or embossed portions of said plates a liquid enamel or vitrifiable substance which is distinctive in color with respect to the color of the back ground, said machine being constructed so as to very rapidly perform its functions and operations and to evenly distribute the enamel or vitrifiable substance over the surfaces of the raised letters or characters.

A further object of my invention is to provide an embossed plate printing machine which is comparatively simple, can be operated with little power and which can be readily adjusted so as to accommodate plates of varying widths.

With the foregoing and other objects in view, my invention consists in certain novel features of construction and arrangement of parts, hereinafter more fully described and claimed.

Referring by numerals to the accompanying drawings, 10 designates a suitable support on which is positioned a pair of upright parallel plates 11 framed together in any suitable manner and arranged between the upper portions of said plates at one end is a feeding table 12 and at the opposite end a discharge or receiving table 13.

Formed in the upper portions of the plates 11 are rectangular notches 14 and projecting upwardly from said plates between every other pair of these notches are blocks 15 in the upper portions of which are formed notches 16. Arranged for rotation in suitable bearings formed in the plates 11 and below the notches 14 is a horizontally disposed row of shafts 17, the same carrying on their central portions plate carrying rollers 18. These rollers are all the same in length and diameter and the shafts 17 are located so that the peripheries of said rollers are substantially in horizontal alinement with the tops of the tables 12 and 13, and thus the plates which are fed from table 12 are carried over by the rollers 18 through the machine and delivered onto table 13.

Comparatively short rollers 19 are located on the shafts 17, said rollers being provided with set screws 20, whereby they may be adjusted on said shafts toward and away from the rollers 18, and formed on each of said rollers 19 is a rib or flange 21. By making the rollers 19 adjustable with respect to the carrying rollers 18, plates of different

widths can be accommodated in the machine, it being understood that said rollers are adjusted so that the edges of the plate engage the ribs 21 and thus the latter serve 5 as guides for the plates during their passage through the machine. (See Fig. 2.)

Fixed on the ends of the shafts 17 on one side of the machine are small sprocket wheels 22 and fixed on the ends of the shafts 13 on the opposite side of the machine are pinions 23. Arranged for rotation in suitable bearings formed in the lower portions 15 of the plates 11 is a main driving shaft 24 and fixed on the end thereof and on the side with the sprocket wheels 22 is a sprocket wheel 25. A sprocket chain 26 passes over all of the sprocket wheels 22 and beneath the sprocket wheel 25, and thus as shaft 24 is rotated, corresponding rotary movement 20 is simultaneously imparted to all of the shafts 17 upon which the carrying rollers 18 are mounted.

Fixed on the end of shaft 24 on the side with the pinions 23 is a pulley 27 which is 25 adapted to receive a driving belt (not shown). Positioned in the notches 14 are journal boxes 28, the same being provided with horizontal extensions 29 which overlie adjacent portions of the plates 11 and screw-seated in these projections 29 are adjacent screws 30, the lower ends of which bear against the upper edges of said plates 11. The shanks of bolts 31 pass through suitable openings formed in the extensions 29 35 and the threaded portions of said bolts are screw-seated in the plates 11. The construction just described provides means for vertically adjusting the journal boxes 28 and locking the same in their adjusted positions.

40 Mounted for rotation in the corresponding pairs of journal boxes 28 are shafts 32, the same being paired with and arranged directly above the shafts 17 and carried by the central portions of these shafts are ink 45 applying or printing rollers 33, the same being preferably formed of rubber or analogous material.

Adjustably mounted on the shafts 32 are rollers 34 provided with bearing ribs 35 and 50 which latter are intended to engage the edges of the plates during their passage through the machine and hold said plates in proper position with respect to the flexible or elastic inking rollers. (See Fig. 2.)

55 Fixed on the ends of the shafts 32 are pinions 36 which are paired and mesh with the pinions 23 and thus the plate carrying rollers 18 and corresponding inking rollers 33 are simultaneously driven toward each other and at the same rate of speed.

Loosely mounted in the notches 16 are the non-circular ends of shafts 37 in the central portions of which are formed intersecting right and left hand threads 38. 65 Loosely mounted on each shaft 37 is an ink

distributing roller 39, the same being provided with a pin or screw 40, the inner end of which engages in the corresponding grooves 38.

It will be understood that the shafts 37 70 are held against rotation and that the rollers 39 rotate upon said shafts by reason of their frictional engagement with the inking rollers 33, and during the rotary movement of said rollers 39 they will reciprocate lengthwise upon the shafts 37 by the engagement of the pins 40 in the intersecting grooves 38. This movement insures an equal distribution of the ink or vitrifiable substance upon the rollers 33 and which rollers apply said ink or vitrifiable substance directly to the surfaces of the raised portions 75 of the plates.

Projecting upwardly from the plates 11 80 is a suitable frame work 41 and adjustably positioned thereupon is one or more containers 42 for the ink or vitrifiable material, the same being discharged onto the ink rollers through valves 43 which are located 85 in the lower ends of said containers.

90 Located on the inner end of the feeding table 12 are guides 44, the same being transversely movable so that they may be adjusted to various widths of plates.

95 In the operation of my improved machine rotary motion is imparted to shaft 24 and by reason of the various driving connections corresponding rotary motion is imparted to the carrying rollers, inking or printing rollers 33, and ink distributing rollers 39. The ink from containers 42 is delivered onto the rollers 33 and as the machine is operated this ink is evenly distributed over the surfaces of said rollers by the rollers 39. The rollers 19 and 34 and guides 44 are adjusted 100 to the width of the plates to be passed through the machine and said plates are now fed from table 11 between the first pair of carrying and inking rollers. This first pair of rollers will frictionally engage the plate 105 and draw the same into the machine and said plate will be successively engaged by the various pairs of rollers and will finally discharge onto table 13.

110 During the passage of the plate through the machine the surfaces of the raised portions will be coated with ink, which it will be understood is a suitable liquid enamel or vitrifiable material, and when said plate is delivered onto table 13, it is in condition 115 to be placed in the drying room or oven.

120 A machine of my improved construction is comparatively simple, requires practically no attention after being properly adjusted, and can be operated at comparatively high speed, and therefore, will very rapidly perform the work required.

125 It will be readily understood that minor changes in the size, form and construction of the various parts of my improved ma- 130

chine can be made and substituted for those herein shown and described, without departing from the spirit of my invention, the scope of which is set forth in the appended claims.

5 I claim:

1. In a machine of the class described, a series of rolling supports, rolling work guides at the ends of said rolling supports, a series of color applying rollers arranged above the rolling supports, work engaging rollers at the ends of said color applying rollers, and means whereby said rolling supports, rolling guides, color applying rollers and work engaging rollers are simultaneously and uniformly driven.

10 2. In a machine of the class described, a support, rolling work guides at the ends of said support, a series of color applying rollers arranged above said support, work engaging rollers at the ends of said color applying rollers, means whereby all of said rollers are simultaneously and uniformly driven, and means for evenly distributing 15 coloring substance to said rollers.

20 3. In a machine of the class described, a series of rolling supports, rolling work guides at the ends of said rolling supports, a series of color applying rollers coöperating with said rolling supports, work engaging rollers at the ends of said color applying rollers, means for simultaneously and uniformly driving the rolling supports, the rolling work guides, the color applying rollers, and the work engaging rollers and color distributing means coöperating with the color applying rollers.

25 4. In a machine of the class described, a series of carrying rollers, rolling work guides arranged at the ends of said carrying rollers and coöperating therewith, a series of color applying rollers, work engaging rollers arranged adjacent to the ends of said color applying rollers, and means whereby 30 the carrying rollers and color applying rollers are simultaneously and uniformly driven.

35 5. In a machine of the class described, a series of carrying rollers, rolling work guides arranged at the ends of said carrying rollers and coöperating therewith, a series of color applying rollers, work engaging rollers arranged adjacent to the ends of said color applying rollers, means whereby the carrying rollers and color applying rollers 40 are simultaneously and uniformly driven, and a series of color distributing rollers coöperating with the color applying rollers.

45 6. In a machine of the class described, a horizontally disposed series of work carrying rollers, a horizontally disposed series of vertically adjustable color applying rollers, means whereby all of the rollers are uniformly and simultaneously driven, adjustable work guiding rollers arranged adjacent to the ends of said work carrying roll-

ers, and work engaging rollers positioned adjacent to the ends of the color applying rollers and above the work guiding rollers.

7. In a machine of the class described, a horizontally disposed series of work carrying rollers, a horizontally disposed series of vertically adjustable color applying rollers, means whereby all of the rollers are uniformly and simultaneously driven, color distributing rollers coöperating with the color applying rollers, adjustable work guiding rollers arranged adjacent to the ends of said work carrying rollers, and work engaging rollers positioned adjacent to the ends of the color applying rollers and above the work guiding rollers.

75 8. In a machine of the class described, a horizontally disposed series of work carrying rollers, work guiding rollers arranged adjacent to the ends of said carrying rollers and having the same axes therewith, which work guiding rollers are adjustable toward and away from said work carrying rollers, a horizontally disposed series of color applying rollers coöperating with the work carrying rollers, and means for evenly distributing coloring matter to said color applying rollers.

80 9. In a machine of the class described, a horizontally disposed series of work carrying rollers, work guiding rollers arranged adjacent to the ends of said carrying rollers and having the same axes therewith, which work guiding rollers are adjustable toward and away from said work carrying rollers, a horizontally disposed series of color applying rollers coöperating with the work carrying rollers, means for evenly distributing coloring matter to said color applying rollers, and means for simultaneously driving the work carrying and color applying rollers.

85 10. In a machine of the class described, a horizontally disposed series of work carrying rollers, work guiding rollers having the same axes with said carrying rollers and adjustable toward and away from said carrying rollers, a horizontally disposed series of vertically adjustable color applying rollers arranged in a plane above the work carrying rollers, and a series of work engaging rollers having the same axes with the color applying rollers and adjustable toward and away from said color applying rollers.

90 11. In a machine of the class described, a horizontally disposed series of work carrying rollers, work guiding rollers having the same axes with said carrying rollers and adjustable toward and away from said carrying rollers, a horizontally disposed series of vertically adjustable color applying rollers arranged in a plane above the work carrying rollers, a series of work engaging rollers having the same axes with the color applying rollers and adjustable toward and 95 away from said color applying rollers.

away from said color applying rollers, and means for simultaneously and uniformly driving the work carrying and color applying rollers.

12. In a machine of the class described, a horizontally disposed series of work carrying rollers, work guiding rollers having the same axes with said carrying rollers and adjustable toward and away from said carrying rollers, a horizontally disposed series of vertically adjustable color applying rollers, a series of work engaging rollers having the same axes with the color applying rollers and adjustable toward and away from said color applying rollers, means for simultaneously and uniformly driving the work carrying and color applying rollers, and means for distributing coloring matter to said color applying rollers.

13. In a machine of the class described, a plurality of shafts occupying the same plane,

a work carrying roller fixed on each shaft, a pair of work guiding rollers adjustably mounted on each shaft with one roller adjacent each end of the corresponding work carrying roller, a series of shafts occupying a plane parallel with the plane occupied by the first series, a color applying roller carried by each of the second mentioned series of shafts, and a pair of work engaging rollers adjustably positioned on each shaft of the second mentioned series of shafts, and which work engaging rollers are positioned adjacent to the work guiding rollers on the first mentioned series of shafts.

In testimony whereof I hereunto affix my signature in the presence of two witnesses, this 3d day of April, 1915.

STEPHEN S. ADAMS.
